UNITED STATES PATENT OFFICE

2,653,043

DOOR CLOSER

Boyd N. Carlson, El Monte, Calif.

Application March 19, 1951, Serial No. 216,437

2 Claims. (Cl. 292—78)

1

This invention relates to door closers in general and in particular to a tension-spring-operated door closer of improved design suitable for doors pivotally mounted on hinges.

There are many designs utilized to close or to retain pivotally mounted doors in closed relationship. The most common is the familiar latch comprising in its simplest form a pivotally mounted member secured to the door itself and adapted to engage an open bracket on the door frame. With this construction the operator must close the door and then manually turn the pivotally mounted member into engagement with the bracket to retain the door in closed relationship. Another familiar device is the spring latch which comprises in a simple form a spring-urged wedge-shaped member positioned in a suitable body member on the edge of the door and adapted to engage a suitable bracket on the door frame. Still another familiar device is the spring-loaded detent which, in a familiar form comprises a seat, which may comprise a metal-lined circular well, is constructed in the floor or door frame. An elongated cylindrical member having a closed rounded outer end is positioned and is urged to its outermost position by a coil spring the inner end of which abuts the bottom of the well. A detent-receiving seat is provided to receive and seat the end of the detent with the door in closed position and is constructed as to effect a retaining action in the absence of a positive displacing force.

Frequently an obstacle to closing and retaining a door in closed position is that the latch, detent or other device relied upon fails properly to engage its cooperative part due to the failure of the operator fully to close the door or to retain it closed for a sufficient period to enable the parts to engage fully.

In an apparatus constructed in accordance with the present device the shortcomings of the prior art are largely overcome while its advantages are largely retained. It is not necessary to hold the door in closed position for any period of time to enable the device to perform its retaining function and the door is permitted free and unhindered pivotal movement when not closed.

An object of the invention is to provide an improved device to engage and retain a pivotally mounted door in closed relationship to its frame.

It is a further object of this invention to provide a device affixed to the door frame which will, upon being contacted by the door, seize, move and positively retain the latter in closed relationship against accidental displacement.

2

It is a further object of this invention to provide a spring action door closer affixed to the door frame which will, upon contact by the door, seize, move and retain the latter in closed relationship.

Still a further object of this invention is to move a door from a substantially closed position to a fully closed position with a positive snap action and to retain it positively in its closed position.

10 Referring now to the drawing:

Figure 1 is an isometric view of a door closer constructed in accordance with the present invention mounted on an ordinary door frame;

Figure 2 is a plan view showing the door closer 15 in its door-engaging position and the pivoted door in its position immediately prior to its engagement therewith or immediately after breaking such engagement;

Figure 3 is a plan view of the door closer and the door frame showing the door in its closed position and the closer in its door-retaining position; and

Figure 4 is a sectional view through the door closer taken on line 4—4 of Figure 3.

20 25 Referring again to the drawing and in particular to Figure 1, a door closer constructed in accordance with the present invention, indicated generally by reference character 10, is shown mounted on the floor or lower horizontal member of a door frame of conventional construction, indicated generally by reference character 8. A conventional door 9 is pivotally mounted on

30 35 hinges 1 (Figure 2) to the upright member of the door frame. A bracket 17 adapted to be engaged by the curved extremity of an arm 16 of the door closer 10 is mounted on the interior face of the door. The door closer 10 is secured to the floor of frame 8 by suitable screws 12 which pass through holes in base plate 11 of the door closer. Base plate 11 has one edge adapted to lie along the front edge of frame 8 and adjacent and parallel to the inside face of the door with the latter closed.

40 45 With the edge of the base plate so positioned the closer arm 16 is properly spaced for cooperation with the door-carried bracket 17, both the closer and the bracket being positioned at the proper distance from the pivot axis of the door as represented by the hinge 1.

Door closer 10 comprises, in addition to base plate 11, two inter-linked parallel plates 13 and 19 pivotally mounted on spaced pins 14 and 21, respectively, fixed in and extended perpendicularly from base plate 11. Plate 13 may be denoted as the arm plate and plate 19 as the follower plate. Arm plate 13 is positioned over and partially overlies follower plate 19, the opposing

surfaces making sliding contact as shown in Figure 4.

Arm plate 13 carries a downwardly extending pin 23 which seats slidingly in open-ended slot 24 in follower plate 19. When arm plate 13 is pivoted about its pivot 14 by a force exerted upon its arm 16 the resultant movement of pin 23 in slot 24 of follower plate 19 causes the latter plate to pivot about the pivot pin 21 in the opposite direction.

An arcuate elongated slot 26 in arm plate 13 slidably encloses the pivot pin 21 of arm plate 13 the ends of the slot serving as stops to limit the pivotal movement of the plate 13. Arm plate 13 is formed along one edge at a distance from arm 16 with a post 29 extending upwardly and to which is secured one end of a tension spring 28, the other end of the spring being affixed to a similar post 27 on the follower plate 19. Pivot pins 14 and 21 are fixed on base plate 11 while posts 27 and 29 are movable with respect to that plate and to the pivot pins. The exact location of the posts is not important so long as they are positioned on their respective plates so as to travel in the same direction across the center line of pins 14 and 21 upon the conjoint movement of the arm plate 13 and follower plate 19.

In Figure 3 the door is shown completely closed and arm 16 of plate 13 has engaged bracket 17 and is threaded through its slot 18. When the door is pulled open bracket 17 slides along arm 16 as arm 16 and its carrying plate 13 pivot counterclockwise against the tension of spring 28. Follower plate 19 simultaneously pivots clockwise from the position shown in Figure 3 to that shown in Figure 2, being connected to plate 13 by the pin and slot connection 23, 24. As arm plate 13 pivots counterclockwise, and follower plate 19 pivots clockwise, post 27 on plate 19 and post 29 on plate 13 and their connecting tension spring 28 pass from one side to the other side of the center line of pivot pins 14 and 21. Obviously upon each side of that center line spring 28 exerts a tension tending to pivot plates 13 and 19 to their end positions determined by the pin and slot connection. The counterclockwise rotation of arm 16 induced by the tension of spring 28 as it passes over center is stopped only when the end of its arcuate elongated slot 26 has reached post 21, as shown in Figure 2. At this point arm 16 has fully disengaged bracket 17 and door 9 is fully released and free to open, as shown in Figure 1.

In Figure 2 the door 9 is shown in a position it assumes in moving to closed position and immediately before contact of bracket 17 with closer arm 16. In this position the arm plate 13 is in its extreme outer or counterclockwise position in which it was left by the door as the latter opened. On closing door 9 the outer face of arm 16 contacts the base of bracket 17, the movement of the door pivoting plate 13 clockwise against the action of tension spring 28 so that the extreme end of arm 16, which is curved to form a hook, engages slot 18. As arm plate 13 pivots clockwise follower plate 19, of course, pivots counterclockwise. This relative movement of the plates moves post 29 and post 27, and spring 28 connected therebetween, from the right of the center line of pins 14 and 21, as viewed in Figure 2, to the left thereof. Tension spring 28 thereupon pivots arm plate 13 clockwise with a snap until stopped upon the end of arcuate elongated slot 26 contacting pin 21, as illustrated in Figure 3. Arm plate 13 is so positioned on base plate 11

that when it reaches this extreme clockwise door-retaining position with bracket 17 engaged, door 9 firmly abuts door frame 8 in a fully closed relationship.

5 In the drawing the door closer 11 is shown mounted on the floor of a conventional cabinet or room with conventional screws 12 inserted through suitable holes provided therefor in base plate 11. However, the closer may be mounted 10 on the frame, or ceiling, or intermediate shelf of the cabinet or room or at any other point, it being important only that the axis of rotation of the door 9 on hinges 7 and the axis of rotation of arm plate 13 on pin 14 be substantially 15 parallel. Further, the closer may be positioned on the underside of a shelf instead of on the upper side thereof, as illustrated in the drawing.

While the particular device herein shown and described in detail is fully capable of attaining 20 the objects and providing the advantages hereinbefore stated, it is to be understood that it is merely illustrative of the presently preferred embodiments of the invention and that no limitations are intended to the details of construction 25 or design herein shown other than as defined in the appended claims.

I claim:

1. In a door closer of the class described, a base plate adapted to be mounted on a fixed member adjacent the inner face of a pivotally mounted door in its closed position, an arm plate having a door-engaging arm mounted on said base plate to pivot about an axis perpendicular to said base plate, a lever extended between said arm plate and said base plate, formed with a slot, and mounted on said base plate to pivot about an axis perpendicular to said base plate, a pin affixed to and extending perpendicularly from the lower face of said arm plate toward said base plate, said pin being slidingly enclosed in said slot in said lever, a tension spring connecting a point on said arm plate to a point on said lever, said points being movable with said plates and so positioned that said spring moves across the line of centers of the pivotal axes of said arm plate and lever upon their pivotal movement in opposite directions, the tension of said spring being adapted to effect relative pivotal movement between said arm plate and said lever upon being moved across said line of centers.

2. In a door closer of the type adapted to engage and move a door into completely closed position and to release said door for free movement after a limited pivotal movement from said completely closed position comprising, a retaining unit adapted to be mounted in a position adjacent the inner face of said door in its completely closed position, said retaining unit including a base plate adapted to be mounted on a fixed surface at a position adjacent the inner face of said door when closed and at a distance from its pivotal axis, a pivot pin fixed to said base plate, a lever plate pivotally mounted on said pin and formed with a slot extended generally toward said pin, a second pivot pin fixed to said base plate, an arm plate pivotally mounted on said second pivot pin at a distance from the pivotal axis of said lever plate and formed with an arm movable, upon the pivotal movement of said arm plate, between an inner position in which it extends substantially parallel to said door with the latter in its completely closed position and an outer position in which it extends at an angle to the door in its closed

position in order to make contact therewith as said door moves from open to closed position and before it reaches its completely closed position, said arm plate also being provided with a member engaging the slot in said lever plate and also formed with a slot enclosing the pivot pin pivotally supporting said lever plate and adapted to limit relative pivotal movement of said arm plate in either direction of pivotal movement by the contact of said pin with the end of said slot, a coil spring connected to said arm plate and to said lever plate at spaced points so positioned relative to the pivot pins of said arm and lever plates as to cause said spring to move across the line of centers of the pivotal 15

axes of said plates as the latter pivot in opposite directions between their end positions, said spring exerting a pivoting force to move said arm and lever plates to their end positions.

BOYD N. CARLSON.
